(57) **CLAIM**

The ornamental design for a wrist pouch, as shown and described.

DESCRIPTION

FIG. 1 is a front perspective view of the present invention.

FIG. 2 is a front elevation view of FIG. 1.

FIG. 3 is a right side elevation view of FIG. 1.

FIG. 4 is a bottom plan view of FIG. 1.

FIG. 5 is a top plan view of FIG. 1.

FIG. 6 is a rear elevation view of FIG. 1; and,

FIG. 7 is a left side elevation view of FIG. 1.

No claim is made to the interior surfaces of the wrist pouch. The phantom and dashed lines in the views form no part of the claimed design and reflect either disclaimed portions of the protective cover surface or are for illustration aids. For example, the zipper is disclaimed as is the top opening region and stitching, as shown in dashed lines. The front surface panel is a mesh portion shown discontinuous for ease but claimed in mesh, which forms a feature of the ornamental claim. No claim is made to the interior portion of the wrist pouch.
